BABY FEEDING DISH

Irving Brecher, 5 Greenacre Court, Great Neck,
Long Island, N.Y.

Filed July 13, 1965, Ser. No. 86,141

Term of patent 7 years

(Cl. D44—15)

FIG.1

FIG. 3

FIG. 4

FIG. 1 is a top perspective view of a baby feeding dish showing my new design; and

FIG. 2 is a bottom view thereof with the power cord omitted for convenience of illustration; and

FIG. 3 is a side elevational view thereof; and

FIG. 4 is a sectional view taken generally along the line 4-4 of FIG. 1.

I claim:

The ornamental design for a baby feeding dish, as shown and described.
